4 - HYDROXYALKYLAMINO - 1,8 - NAPHTHALIC
ACID IMIDE DYE SALTS OF OIL-SOLUBILIZING
QUATERNARY AMMONIUM HALIDES

Arthur F. Klein, Holland, Pa., assignor to American Cyanamid Company, New York, N.Y., a corporation of Maine

No Drawing. Filed Mar. 10, 1961, Ser. No. 94,678

8 Claims. (Cl. 260—281)

The present invention relates to a novel process for coloring non-polar solvents; making use of available, oil-insoluble 4-hydroxyalkylamino-1,8-naphthalic acid imide dyes which previously could not be used for this purpose. It also contemplates the color-characterizing of liquid fuels. Still more specifically, the invention presents novel, fluorescent, oil-soluble, colored quaternary ammonium reaction products of oil-insoluble, substituted 4-hydroxyalkylamino-1,8-naphthalic acid imide dyes. It also presents these reaction products in concentrated non-polar solvent solutions which can be easily metered into large quantities of any non-polar solvent. Resultant colored solvents exhibit no functional impairment and are characterized by uniform fluorescent shades, easily detectable both in daylight and "black" light.

In general, the present invention may be used to color non-polar solvents. As contemplated in the present invention, the term "non-polar solvents" includes various organic liquid fuels and solvents. They may be classified generally into two broad groups; Group (I) being those of natural origin, and Group (II) synthetic compositions of matter.

Group (I) includes those derived naturally-occurring hydrocarbons such as petroleum ether, having a boiling point of about 20°-60° C.; light naphtha, having a boiling point of about 60°-100° C.; gasoline, having a boiling point of about 40°-205° C.; kerosene, having a boiling point of about 175°-325° C.; lubricating oils and the like. Depending upon the geographical location from which the crude oil base is obtained from which naturally-occurring hydrocarbons are derived, these bases may be divided into three general types: Type (1), which herein designates the paraffinic type; Type (2), the aromatic type; and Type (3) the mixed type.

The synthetics of Group (II) include such generally synthesized non-polar compounds as carbon tetrachloride, benzene, tetramethyl methane and the like.

For purposes of simplication, novel colored preparations of this invention will be referred to as "colorants for jet fuels." However, it is to be understood that the term "jet fuel" as used herein also includes such other fuels and solvents as those noted above, as illustrative.

By way of further illustration, the aircraft industry over the years has developed many types of motor. Some advantageously may use low-octane gasoline. Others require high-octane gasoline for maximum performance. More recently so-called "jet" motors, which utilize such "jet" fuels as kerosene and the like, have become important. With the ever increasing use of jet planes, they are found based on locations all over the world. Consequently, there is a need for "jet fuels," as well as various grades of gasoline in widely divergent locations. Furthermore, auxiliary landing fields, with reserve fuel supplies, are required. In such locations, fuels often are delivered and stored in drums. Frequently, too, refueling may be necessary at night. Should this occur, precautions are necessary to insure that each particular plane is serviced with the required type of fuel. Unless these fuels are characteristically marked so that they may be readily identified by night as well as by day, there is a real danger that the wrong fuel might be used.

2

For these reasons, colorants for such fuels must meet at least 3 requisites, among others.

(1) The colorant should be soluble in all three types of non-polar solvent fuel.

5 (2) The colorant should be highly and completely oil-soluble, producing no deposits or sludge when used in formulating colored concentrate solutions suitable for metering into the fuels.

(3) The so-colored fuel should be distinguishable in 10 "black" light as well as daylight.

The term "black" light as used in this invention refers to *ultraviolet* light which is invisible to the unaided human eye.

15 Since the primary purpose is to obtain a characteristic coloring of non-polar solvents including those from bases of Types (1), (2) and (3), it should be noted that to be considered successful, a procedure according to the present invention must meet three additional criteria. It should impart a characteristic, fluorescent, bright color to 20 the jet fuel which will serve to distinguish it in all places at all times. Moreover, the color should be stable, particularly to sunlight. Finally, such a product should be easily and simply prepared.

25 Gasolines and kerosenes may be and generally are mixtures of many hydrocarbons, including those that are derived from more than one of the three types of base noted above as Type (1), Type (2), and Type (3). Consequently, a jet-fueled plane, of necessity may use fuel from any or all three types. Accordingly a colorant used 30 to characterize jet-fuel, for example, must be highly soluble in each of all three types.

35 Most presently-used, oil-soluble dyes in general are simple aromatic compounds as compared with many dyes, having relatively few amino, hydroxy, or azo groups and they generally are soluble in hydrocarbons from bases of Types (2) and (3). However, many, if not most, such oil-soluble dyes are noted for their poor solubility in paraffinic hydrocarbons from Type (1). Accordingly, 40 they are unacceptable for the preparation of a universally useful concentrate, characteristically colored, and suitable for metering into hydrocarbon solvents, including hexane, heptane, octane, decane, jet fuels, and the like, derived from Type (1). Presently-used oil-soluble dyes also suffer the further drawback of not being characterized by brilliant fluorescence.

45 Despite the wide use of these natural non-polar solvents, in the past there has been available no satisfactory, simple process by which they can be satisfactorily color characterized. This problem has proved particularly troublesome with respect to the natural hydrocarbons derived 50 from Type (1) which, in general, are the most difficult to color. Surprisingly, in view of the commercial importance of colorants for characterizing jet fuels and the contemplated dyes for the purpose, in the past it has not 55 been possible to accomplish satisfactory coloring using known dyes. It is a principal advantage of this invention that it fills this need.

Even more surprising is the fact that despite the long 60 felt want of such a process and colorants therefor, it has been met in the present invention not only to a surprisingly successful degree but by the relatively simple expedient of converting suitable known dyes into their quaternary salts of a particular class of quaternary halides. It thus provides a simple suitable coloring process 65 for non-polar solvents, particularly for jet fuels, derived from all of Type (1), (2) and (3) bases. It makes possible the preparation of a concentrated solution in hydrocarbon solvents which may be easily metered into jet fuels, imparting thereto bright, fluorescent, characteristic colors. The unexpectedly brilliant fluorescence of the 70 colored fuel is particularly surprising. Last but not least, no observable sedimentation is encountered.

TYPES OF DYES UTILIZED

As noted above, one of the purposes of this invention is to provide a process by which Type (1) jet fuels can be quickly and characteristically colored, making use of known available dyes which previously could not be so employed. To this end, it is contemplated that this invention may utilize available dyes from the known class of substituted 4-hydroxylalkylamino-1,8-naphthalic acid imide dyes. These dyes generally correspond to the following formula

in which R is an alkylol group of less than four carbon atoms and R' is a saturated hydrocarbon of less than seven carbons. Specific examples of such dyes will be used below, for purposes of illustration. To simplify reference thereto they will be designated Dyes "(A)," "(B)," "(C)" and "(D)" respectively, as follows:

- Dye (A): 4- β -hydroxyethylamino-1,8-naphthalic acid N-butylimide
 Dye (B): 4- β -hydroxyethylamino-1,8-naphthalic acid N-amyliamide
 Dye (C): 4- β -hydroxypropylamino-1,8-naphthalic acid N-amyliamide
 Dye (D): 4- β -hydroxyethylamino-1,8-naphthalic acid N-cyclohexylimide

The above dyes and others are described in U.S. Patent 2,415,373. They are insoluble in hexane which is generally used as a test solvent for solubility in hydrocarbons from Type (1) bases. For simplification of identification, such dyes will be referred to below as a class by the designation the "dyes."

TYPES OF QUATERNARY COMPOUNDS UTILIZED

As indicated above, dyes utilized in this invention are substituted 4-hydroxylalkylamino-1,8-naphthalic acid imides. They are not soluble in hexane. Unexpectedly, it has been found that they may be made highly and completely oil-soluble by forming a reaction product with certain quaternary ammonium salts. Quaternary salts to be useful in this invention should have at least three special properties:

- (1) They should be water-insoluble,
 (2) They should be free of hydrogen attached to nitrogen, and
 (3) They should be tetra-alkyl quaternary ammonium halides having one or two short-chain alkyl groups and two or three "long-chain alkyl" groups.

Suitable halides include chlorides and bromides. When referred to below by the class designation "halides" it is understood the term is intended to be limited thereto. Suitable short-chain alkyls are methyl, ethyl, propyl, butyl or amyl. Suitable "long-chain alkyl" groups should contain an average of at least nine but not more than twenty carbon atoms and not only may be saturated (alkyl) or unsaturated (alkenyl) groups, but the same "halide" may contain both. Advantageously, for example, they may contain such mixtures of alkyl and alkenyl groups as are present in such commercially-available oils such as coconut, soya, tallow and the like. Because such commercially-available compositions are not pure products, they will be discussed more fully below, under their ordinary commercial designations "coco," "soya" and "stearyl," respectively.

It is uncertain just what product is formed by the "reaction" of the dyes of this invention and such illustrative tetra-alkyl ammonium halides as those noted above. A

5 chemical reaction may occur, but the invention is not limited to such a theory. Again, for simplicity in designation, colored products obtained in this "reaction" will be referred to below as the "quaternary salt of the dye" or as the "dye salt."

10 The amount of halide to be employed is critical. Sufficient halide must be present to completely react with the dye and provide an excess of at least about 0.25 mols per mol. Thus, one molecular weight (average) of the halide per mol of the dye can be reacted but it requires a longer reaction time. Unfortunately and surprising, the resultant dye salt does not impart the desired brilliant shade of fluorescence to hexane and other hydrocarbons of Type (1). To obtain the desired fluorescence a larger quantity 15 of halide must be used. An excess up to a molar ratio of halide to dye of about ten to one produces excellent results. Such a large excess adds unnecessarily to the overall expense and ratios above about 5:1 are not usually warranted. Ratios of from about 1.25:1 to about 5:1 produce satisfactory results and constitute the preferred range.

REACTION TEMPERATURES

20 Although the temperature at which the reaction between the halide and the dye is conducted is important, it is less critical than the molar ratio. Temperatures in the range of from about 100° to about 250° F., may be employed. The higher temperatures are used only for those halides having higher melting points. Use of a temperature in the range of from about 125° to about 225° F. is generally 25 satisfactory and constitutes a good general practice.

REACTION TIME

30 While the reaction time depends to some extent on temperature, a time in the range of from about 10 to about 20 minutes have been found generally sufficient to produce reaction products having satisfactory solubility in hexane as the typical test solvent. However, the reaction should be continued until at least ten grams of the reaction product dissolves readily in 90 grams of hexane without any residual detectable sediment or sludge.

35 In general terms, preparation of the dye salts according to this invention may be simply described.

- (1) In a suitable container, the halide is heated to about 40 150° F.; the halide should be well softened or melted. If not the temperature is increased until this occurs.
 (2) The dry dye then is added slowly, with stirring, to the heated halide.
 (3) Heating and stirring are continued until the reaction 45 between the quaternary halide and the dye is sufficiently completed, i.e., until as noted above at least ten grams of the dye salt dissolves in 90 grams of hexane to a clear, bright color with no observable sedimentation.

50 Thereafter, concentrated solutions of the dye salt are prepared using any, or all, of the hydrocarbons including those from Types (1) (2) and/or (3). Resultant concentrated solutions should contain from about 0.1 to about 10% of the reaction product. These concentrated solutions may be sent anywhere for coloring "native" non-polar solvents including jet fuels. Alternatively, the dye salt may be shipped per se with suitable instructions and used wherever so-desired to produce the colored concentrates for metering into the large masses of non-polar solvents to be colored.

55 As noted above, colored concentrated solutions may also be used for other purposes as by being thickened with an oil-soluble cellulose derivative, or its equivalent. It also may be converted into emulsions for use in coloring various fibrous or other materials, including sheets, films, resins, yarns, fabrics and the like.

60 It is a still further advantage that jet fuels colored with about 0.002-0.01% weight percent of the above colorants will acquire bright, characteristic fluorescent shades using any one, or a combination, of hydrocarbons from Types (1) (2) and (3).

The invention will be further illustrated in conjunction with the following discussion and the accompanying examples of the use of the tetra-alkyl ammonium halides. These examples are illustrative only. Therein, unless otherwise noted, all parts and percentages are by weight and temperatures are in Fahrenheit degrees. Reactions are described using molar quantities of the halide and Dyes (A) (B) (C) and (D) noted above. The number 267 was used as the molecular weight of trimethyl mono-“coco” ammonium chloride; the number 450 was used as the molecular weight of di-methyl-di-“coco” ammonium chloride; the number 566 was used as the molecular weight of di-methyl di-“soya” ammonium chloride; and the number 571 was used as the molecular weight of di-methyl di-“stearyl” ammonium chloride. Molecular weights of the di-“ethyl,” di-“propyl,” di-“butyl” and di-“amyl” compounds may be easily calculated from the above numbers if necessary or so desired.

In the following Examples 1-7, the halide is reacted with the dye according to the following procedure.

- (1) Weigh the required equivalent quantity of the trimethyl mono-“coco” ammonium chloride and enter into a container equipped with a stirrer.
- (2) Heat the quaternary salt to about 150° F.
- (3) Weigh one equivalent quantity of the dry imide dye and add to the liquid quaternary compound slowly, with stirring.
- (4) Continue heating and stirring at about 150° F. until a clear solution is obtained.
- (5) Cool to room temperature, with stirring.

Solubility tests of the reaction products is observed by stirring one gram of the colored dye salt into 100 ml. of the test solvent.

To demonstrate the unsatisfactory nature of dye salts from halides containing three short-chain alkyl groups and only one long-chain, in the following example a commercially-available trimethyl-mono-“coco” ammonium chloride was used. The “coco” portion of the quaternary compound is a mixed commercial “alkyl” comprising generally about 8% octyl, 9% decyl, 47% dodecyl, 18% tetradecyl, 8% hexadecyl and 10% octadecyl groups. The equivalent or molecular weight of the chloride is calculated to be about 267.

Example 1

Four reaction products of each of the four dyes (A) (B) (C) and (D) are prepared using the following ratios: (a) one equivalent of the chloride and one equivalent of each dye; (b) 1.25 equivalents of the chloride and one equivalent of the dye; (c) four equivalents of the chloride and one equivalent of imide dye; and, (d) eight equivalents of the chloride and one equivalent of the dye. The sixteen resultant products are then tested for the solubility of one gram of dye salt in 100 grams each of water and of kerosene as a typical jet fuel. Results are summarized in the following Table I.

TABLE I

Dye	Equivalents of Dye	Equivalents of Halide	Soluble in—	
			Water	Kerosene
(A)	1	1	No.	No.
(A)	1	1.25	No.	No.
(A)	1	4	Cloudy	No.
(A)	1	8	Yes	No.
(B)	1	1	No.	No.
(B)	1	1.25	No.	No.
(B)	1	4	Cloudy	No.
(B)	1	8	Yes	No.
(C)	1	1	No.	No.
(C)	1	1.25	No.	No.
(C)	1	4	Cloudy	No.
(C)	1	8	Yes	No.
(D)	1	1	No.	No.
(D)	1	1.25	No.	No.
(D)	1	4	Cloudy	No.
(D)	1	8	Yes	No.

It may be observed from Table I that, none of the reaction products are soluble in kerosene; when the ratio of the tri-methyl mono-“coco” ammonium chloride is in a range of about 4-8, the colored reaction products are water-soluble; the 4:1 product showing slight cloudiness, indicating incomplete solubility, but however, the 8/1 product give a clear solution indicating complete solubility in water.

To illustrate the effect of halides having both two short and two long-chain “alkylo” groups the following example was carried out using a commercially-available di-methyl-di-“coco” ammonium chloride. The equivalent or molecular weight of the chloride is calculated to be about 450.

Example 2

The procedure of Example 1 is repeated but substituting the above-noted chloride for that of Example 1, four reaction products being prepared for each of the four dyes. The results are summarized for the sixteen products in the following Table II.

TABLE II

Dye	Equivalents of Dye	Equivalents of Halide	Soluble	
			Water	Kerosene
(A)	1	1	No.	Sl. Cloudy.
(A)	1	1.25	No.	Yes (clear).
(A)	1	4	No.	Do.
(A)	1	8	No.	Do.
(B)	1	1	No.	Sl. Cloudy.
(B)	1	1.25	No.	Yes (clear).
(B)	1	4	No.	Do.
(B)	1	8	No.	Do.
(C)	1	1	No.	Sl. Cloudy.
(C)	1	1.25	No.	Yes (clear).
(C)	1	4	No.	Do.
(C)	1	8	No.	Do.
(D)	1	1	No.	Sl. Cloudy.
(D)	1	1.25	No.	Yes (clear).
(D)	1	4	No.	Do.
(D)	1	8	No.	Do.

As compared with Table I it will be seen that excellent solubility in kerosene is obtained in the range halide: dye ratios of about 1.25:1 to about 8:1; *none* of the products is water soluble. The reaction products formed using the 1:1 ratio show slight cloudiness in kerosene, indicating that this reaction product is not as completely soluble as the others.

Example 3

Twenty parts of dye salt, prepared above in Example 2 from Dye (A) and chloride in 1:4 ratio are dissolved in 80 parts of kerosene, imparting to the nonpolar solvent a bright, greenish-yellow, fluorescent color. The dye salt is also equally soluble in equivalent amounts in hexane, gasoline, and jet fuel.

The 20% solution in kerosene is metered into one gallon of kerosene to give about 0.001-0.01% concentration. A characteristic greenish-yellow, fluorescent color is imparted. This characteristic color is visible both in daylight and in black light.

Example 4

The procedure of Example 2 is repeated, using as the halide a commercially-available di-methyl di-“soya” ammonium chloride instead of the di-methyl di-“coco” ammonium chloride. The “soya” component comprises about 24% hexadecyl, 4% octadecyl, 30% octadecenyl, and 42% octadecadienyl components. The molecular or equivalent weight of this compound is calculated to be about 566. Colored dye salts of the twelve reaction products obtained in the ratios from a range of 1.25:1; 4:1; and 8:1 are readily soluble in hexane, gasoline, kerosene, and jet fuel.

Example 5

Twenty parts of the "quaternary salt of the dye," prepared in Example 4 from Dye (A) using the 4:1 ratio are dissolved in 80 parts of kerosene, imparting a bright, greenish-yellow, fluorescent color to this non-polar solvent. This reaction product also is equally soluble in hexane, jet fuel and gasoline. Portions of the above concentrated solution are metered into lubricating oils having S.A.E. ratings of 10, 30 and 60. In each instance, a characteristic greenish-yellow, fluorescent color is imparted to the oil.

Example 6

Portions of the concentrated solution produced in Example 5 are metered into kerosene to give a concentration of the colored component of about 0.002%. A greenish-yellow, fluorescent color results which is visible in daylight and in black light. When the concentration of the colored component is increased to about 0.0075%, the greenish-yellow, fluorescent color is intensified.

Example 7

The procedure of Example 2 is repeated substituting a commercially-available quaternary salt, di-methyl di-"stearyl" ammonium chloride. The "stearyl" component comprises about 75% octadecyl, 24% hexadecyl, and 1% octadecenyl components. The molecular weight of this compound is calculated to be about 571. Colored reaction products of the various dyes prepared in the ratio range of from about 1.25:1 to about 8:1 are soluble in gasoline and kerosene.

Example 8

Ten parts of the reaction product, prepared in Example 7 from Dye (A) at the 4:1 ratio are dissolved in 90 parts of gasoline. Sufficient of this concentrated solution is then metered into one gallon of jet fuel to give a concentration of the colored component of about 0.001% on the weight of the jet fuel. A characteristic, greenish-yellow, fluorescent color is imparted to the jet fuel. It is readily distinguished in daylight and in black light. When the concentration of the colored component is increased to about 0.01%, this characteristic color is intensified.

Example 9

Using one equivalent of Dye (A) and four equivalents of di-methyl di-"coco" ammonium chloride, the procedure of Example 2 is repeated at a temperature of about 175° F. The resulting dye salt is soluble in gasoline and kerosene. In coloring effectiveness the product is the equivalent of the corresponding product obtained in Example 2.

Example 10

Example 9 is repeated, using a reaction temperature of about 225° F. The reaction between the dye and chloride is very rapid at this temperature. The product is substantially the same, being soluble in gasoline, and imparting a characteristic, greenish-yellow, fluorescent color to the non-polar solvent.

I claim:

1. A water-insoluble colored salt, soluble in non-polar solvents, comprising a dye salt produced by melting together at about 100°-250° F. until a clear hexane-soluble product is obtained (a) from about 1.25 to about 10 moles and sufficient to completely react with the dye of a halide of the formula

wherein (Hal) is selected from the group consisting of chlorine and bromine; each R¹ is a long-chain hydrocar-

10

bon selected from the group consisting of alkyl and alkenyl containing from about nine to about twenty carbons; R² is an alkyl of less than six carbon atoms; and R³ is selected from R¹ and R²; and (b) one mole of an N-substituted 4-hydroxyalkylamino-1,8-naphthalic acid imide of the formula

15

wherein R is an alkylol having less than four carbons and R¹ is a saturated hydrocarbon of less than seven carbons.

2. A method for the preparation of the dye salt of claim 1 comprising the steps of heating said tetra-alkyl quaternary ammonium halide until liquification occurs, then adding the dry imide dye slowly, with stirring, at a temperature in the range of from 100° F. to about 250° F., and continuing heating and stirring until 10 parts by weight of the product is soluble in 90 parts of hexane.

3. A water-soluble colored salt, soluble in non-polar solvents, comprising a dye salt produced by melting together at about 100°-250° F. until a clear hexane-soluble product is obtained a quantity sufficient to completely react with the dye and within the range of from about 1.25 to about 10 mols of di-"coco"-dialkylammonium chloride in which each of the two alkyls contains less than six carbon atoms and one mol of an N-substituted 4-hydroxyalkylamino-1,8-naphthalic acid imide of the formula

40

wherein R is an alkylol having less than four carbons and R' is a saturated hydrocarbon of less than seven carbons.

4. A water-soluble colored salt, soluble in non-polar solvents, comprising a dye salt produced by melting together at about 100°-250° F. until a clear hexane-soluble product is obtained a quantity sufficient to completely react with the dye and within the range of from about 1.25 to about 10 mols of di-"soya"-dialkylammonium chloride in which each of the two alkyls contains less than six carbon atoms and one mol of an N-substituted 4-hydroxyalkylamino-1,8-naphthalic acid imide of the formula

50

wherein R is an alkylol having less than four carbons and R' is a saturated hydrocarbon of less than seven carbons.

5. A water-soluble colored salt, soluble in non-polar solvents, comprising a dye salt produced by melting together at about 100°-250° F. until a clear hexane-

60

65

70

75

soluble product is obtained a quantity sufficient to completely react with the dye and within the range of from about 1.25 to about 10 mols of di-“stearyl”-dialkylammonium chloride in which each of the two alkyls contains less than six carbon atoms and one mol of an N-substituted 4-hydroxyalkylamino-1,8-naphthalic acid imide of the formula

wherein R is an alkylol having less than four carbons and R' is a saturated hydrocarbon of less than seven carbons.

6. A water-soluble colored salt, soluble in non-polar solvents, comprising a dye salt produced by melting together at about 100°-250° F. until a clear hexane-soluble product is obtained a quantity sufficient to completely react with the dye and within the range of from about 1.25 to about 10 mols of tri-“coco”-monoalkylammonium chloride in which the alkyl contains less than six carbon atoms and one mol of an N-substituted 4-hydroxy-alkylamino-1,8-naphthalic acid imide of the formula

wherein R is an alkylol having less than four carbons and R' is a saturated hydrocarbon of less than seven carbons.

7. A water-soluble colored salt, soluble in non-polar solvents, comprising a dye salt produced by melting together at about 100°-250° F. until a clear hexane-soluble product is obtained a quantity sufficient to completely react with the dye and within the range of from about 1.25 to about 10 mols of tri-“soya”-monoalkylammonium chloride in which the alkyl contains less than six

carbon atoms and one mol of an N-substituted 4-hydroxy-alkylamino-1,8-naphthalic acid imide of the formula

wherein R is an alkylol having less than four carbons and R' is a saturated hydrocarbon of less than seven carbons.

15 8. A water-soluble colored salt, soluble in non-polar solvents, comprising a dye salt produced by melting together at about 100°-250° F. until a clear hexane-soluble product is obtained a quantity sufficient to completely react with the dye and within the range of from about 1.25 to about 10 mols of tri-“stearyl”-monoalkylammonium chloride in which the alkyl contains less than six carbon atoms and one mol of an N-substituted 4-hydroxy-alkylamino-1,8-naphthalic acid imide of the formula

35 wherein R is an alkylol having less than four carbons and R' is a saturated hydrocarbon of less than seven carbons.
